PREFORMED DENTAL ARCH

Eric H. Zahn, Kirkland, Wash.

Application April 25, 1949, Serial No. 89,411

4 Claims. (Cl. 32—2)

1

This invention relates to improvements in preformed dental arches for use in human dentures, and, more particularly, relates to providing adjustability in and between the parts of sectional dental arches to accommodate a single arch to several different widths of jaw in persons being fitted with dentures.

The art of producing dentures has usually, in the past, involved the assembly of many single and individual teeth into a set which can be mounted and finally associated together into a denture. The operator has had the problem of selecting tooth by tooth the set which he then mounts tooth by tooth in a pattern holding material such as wax. This is tedious and painstaking work and requires great skill. Relatively recently it has become possible, as more fully shown in my application Serial No. 50,337, now abandoned, to produce preformed dental arch blocks in which several teeth are securely joined together in side-by-side relationship to provide a unit that can be handled roughly and mounted quickly. However, it is difficult to produce a full arch in a single casting operation and such is likewise not adjustable; consequently, each denture requires a separate mold and amounts to a special or custom job.

Having in mind these and other criticisms of the prior practices, I disclose my invention which is based upon the following general objects:

An important object of this invention has been the provision of a preformed dental arch, for use in artificial dentures, that is adjustable to permit variation of the width of the arch horizontally in the occlusal plane to accommodate with a single arch a plurality of jaw sizes and shapes.

Another object of the invention has been to provide an adjustable preformed dental arch in which the adjustment of the arch width can be accomplished manually but without distortion of the arch from the occlusal plane.

Still another object of this invention resides in the provision of a dental arch construction that lends itself to preformation and permits production of occlusally matching maxillae and mandible sections that can be similarly adjusted to vary the arch width but without disruption of the occlusion therebetween.

A further object of the invention is the provision in a preformed dental arch of means permitting adjustment of the arch width but which means is relatively more flexible in the occlusal plane than in a vertical or distorting direction out of said plane.

One other object of the invention is to provide

a preformed dental arch which may be quickly and conveniently adjusted manually to vary the width of the arch without requiring an unduly high degree of skill.

A still further object of the invention is the provision of an adjustable and sectional preformed arch that is simple and easy to produce and which will accommodate a wide variety of conditions but without requiring a similar plurality of individual arches.

Another and further object of this invention has been the provision of a jointed sectional dental arch that is simple to mold in sections and easy to assemble into a unit.

Other objects and advantages of my invention will be more apparent from the following specification when read in view of the accompanying drawings, in which:

Figure 1 is a perspective view of a sectional dental arch with the sections or blocks of teeth disassembled for convenience of illustration;

Figure 2 is a plan view of a dental arch according to my invention;

Figure 3 is an enlarged view in elevation of a dental arch according to my invention;

Figure 4 is a further enlarged view in elevation of the abutting ends of a pair of toothed blocks joined according to my invention with portions broken away and shown in section for convenience of illustration;

Figure 5 is a perspective view of a symmetrical hinge bar used in my invention; and

Figures 6, 7 and 8 are cross-sectional views of alternative types of bar stock suitable to form my symmetrical hinge bar.

In brief, the invention resides in the provision of inflexible blocks of teeth that are mounted together in a side-by-side arrangement to form anterior or posterior block sections. Such sections are joined together in alignment by hinge bars that, by being formed symmetrical in their major, minor and longitudinal axes, are manually flexible in the plane of the minor axis and relatively inflexible out of said plane by normal manual pressure. Such joined together and flexibly hinged sections comprise a full dental arch that can be adapted, by flexing the hinge bars, to various widths of jaw to be accommodated. A carrying forward of the inventive thought includes the concept of forming paired upper and lower arches that have proper occlusion and yet, by being flexible between the anterior and posterior sections, can be inwardly or outwardly adjusted without disruption of the occlusion previously obtaining between the arches. It is highly

important that, despite the flexing of the sections inwardly or outwardly in the occlusal plane, each arch must be relatively inflexible upward or down. For this latter reason, I have found that the use of a hinge bar that is symmetrical in both its major and minor axes and has a uniform cross-section along its length is most desirable and efficacious.

Referring particularly to Figures 1 and 2 of the drawings, I show a dental arch having a multi-toothed anterior block 10 and the multi-toothed posterior blocks 12, 12. The teeth of each block are preferably joined securely together in the proximal region to make the blocks substantially inflexible between their ends. Such blocks, I have found, are most effectively produced by precision casting methods and the use of synthetic or plastic polymerizable materials whereby life-like reproductions can most conveniently be made. In such casting operations, through the use of a withdrawable core member, I form mortises or sockets 14, which are accurately located and preferably enter the body of the end tooth of a block in the proximal contact region.

The posterior teeth blocks 12 need only have a mortise 14 on the forward end in the first bicuspid tooth 16, whereas the anterior block 10 has a mortise 14 at the ends in each cuspid tooth 18.

The dowel-like hinge bar 20 of Figure 5, which is rectangular in cross-section, fits into the mortises 14 of teeth 16 and 18 as when a posterior block 12 is brought into abutment with the anterior block 10. The hinge bar 20 closely fits the mortises to eliminate looseness and prevent racking of the blocks relative to each other. The hinge bars may be secured in the mortises cementitiously, on occasion, although I have found that insuring a close fit between bar and opening is usually sufficient.

It will be seen in Figure 5 that the bar 20 is symmetrical in its major axis A—A, its minor axis B—B, and its longitudinal axis C—C. This characteristic is important because it insures that when the bar 20 has its longitudinal axis C—C bent in the plane of axis B—B, the bend will not tend to distort the bar out of that plane. In other words, the bend should be in a substantially flat plane corresponding generally to the occlusal plane and bending out of that plane is resisted by forming the bar so that its width is greater than its horizontal thickness.

Such a bar 20 is placed between the blocks 10 and 12 so the width is upright and the thickness is substantially horizontal. The ends of the bar are embedded in the cuspid and first bicuspid teeth of the abutting sections and the bar spans between such teeth at the proximal contact region where it is effectively concealed and is not exposed to view.

Bar 20 is most effective when formed of a metallic material that is rust-proof and has a ductility that permits manual flexing in the horizontal plane but is practically inflexible out of that plane by normal manual pressure.

An operator starting to produce a denture and having the assembly of Figure 2, determines the jaw breadth that this arch is to accommodate. He adjusts the dental arch by manually flexing or bending the hinge bars 20 inward or outward to move the posterior sections relative the anterior section in the occlusal plane. Since normally the abutment between an anterior and a posterior section is not broad or substantial, the

bending of the bar is not interfered with by the adjacent tooth material which usually curves away from the point of contact. Because of the relative inflexibility of the bars 20 out of the plane of bending, such an operator will not normally by manual pressure distort one section upward relative the other.

In the case of a pair of matched dental arches having proper, predetermined occlusion there-between, accurate adjustment is entirely possible and quite easy of attainment. The operator moves, let us say, the lower posterior blocks outward a desired amount and then moves the upper posterior blocks a like amount, retaining the previously had occlusion between the arches.

Bar 24 of Figure 6 is an alternative form of the shape of a fully symmetrical oval. Bar 26 seen in Figure 7 is I-shaped by reason of flanges 27 and is likewise symmetrical in the sense employed herein. The further alternative form of hinge bar 28 of Figure 8 is similar to the rectangular bar 20, except that its edges are beaded at 30. The bars of Figures 7 and 8 are somewhat stiffer than bar 20 but are so formed as to nevertheless be manually flexible in the plane B—B and relatively inflexible to manual pressure out of that plane. It will be understood that the use of bars 24, 26 or 28 will necessitate the formation of mortises that are shaped to receive such bars.

I have found that this invention produces many advantages that are material in the production of artificial dentures. By the use of arches having my invention incorporated easy accommodation of a wide range of sizes in the human mandible and maxillae can be had with a single standard arch. This means that the stock of arches that must be maintained in a laboratory is relatively small and expense of large inventories is avoided. The setting-up of teeth can be accomplished with help of materially less skill than in the case of the present conventional methods and in considerably less time by such unskilled technicians. The use of preformed anterior blocks permit the selection and trying-on of the block to the patient for size, color and tooth arrangement without elaborate laboratory work having to be done beforehand, thus eliminating at least one visit of the patient. The esthetics of supplying artificial dentures is materially enhanced and patient satisfaction is more easily attained. Another advantage that I have noted to be of importance is that the laboratory worker is precluded from changing the vertical dimensions and altering occlusion during processing of the teeth—in other words, he can follow a bite register furnished and does not risk changing the bite between matched upper and lower arches. Balanced occlusion can be obtained once in a master set and then can be reproduced time after time in the preformed arches having such balanced occlusion and maintained despite alterations of the arch width and with the avoidance of spot grinding and milling which are time-consuming and expensive operations at present.

Having thus fully described and explained my invention, I claim:

1. A dental arch, comprising: three end-abutting inflexible blocks of artificial teeth, the teeth of each block being securely fused to its neighbors in the interproximal region, each block forming an integral, self-supporting assembly independently of gum denture structure, a first of said blocks being composed of the posterior teeth

on one side from a point in the **cuspid-bicuspid** area rearward, a second of said blocks being composed of the posterior teeth on the other side from a point in the **cuspid-bicuspid** area rearward, and the third of said blocks being composed of the anterior teeth between said first and second blocks, said blocks having openings in their adjacent abutting ends; and, means joining said first block to said third block and said second block to said third block, said means comprising an elongated, transversely and longitudinally symmetrical metal hinge bar embedded at its ends in said openings in said blocks contiguous to the interproximal region on each side of the line of abutment, said hinge bar having larger transverse dimensions vertically than horizontally and being manually flexible in a substantially horizontal plane and relatively inflexible out of said plane by normal manual pressure.

2. The invention according to claim 1 in which the hinge bar is a transversely oblong rectangular bar positioned so that its greatest transverse dimension is upright.

3. The invention according to claim 1 in which the hinge bar is a bar having beaded edges throughout its length and so positioned that its width is upright.

4. The invention according to claim 1 in which the hinge bar is a bar having an I-shape in cross-section throughout its length and so positioned that its width is upright.
